UNITED STATES PATENT OFFICE.

ANTHONY F. NUGENT, OF NEW YORK, N. Y.

AWNNG-FASTENER.

1,125,589.

Specification of Letters Patent.

Patented Jan. 19, 1915.

Application filed July 8, 1914. Serial No. 849,742.

To all whom it may concern:

Be it known that I, ANTHONY F. NUGENT, a citizen of the United States, and a resident of the city of New York, borough of Manhattan, in the county and State of New York, have invented a new and Improved Awning-Fastener, of which the following is a full, clear, and exact description.

The object of the invention is to provide 10 a new and improved awning fastener arranged to permit of quickly and conveniently connecting the top edge of an awning with the permanent attaching members on the window of a building or other structure 15 on which the awning is to be used.

In order to accomplish the desired result 20 use is made of a carrier slidably engaging the upper thickened edge of the awning covering, and a yoke pivoted on the said carrier and adapted to assume an angular position 25 and an alined position relative to the carrier, the yoke when in angular or open position permitting of engaging the fastener with the fixed attaching member, and the yoke 30 when in alined or closed position being held locked by the pull exerted upon the awning covering.

A practical embodiment of the invention 35 is represented in the accompanying drawings forming a part of this specification, in which similar characters of reference indicate corresponding parts in all the views.

Figure 1 is a side elevation of the awning fastener with the carrier and yoke in position 40 for engaging the attaching member fixed on the building, the building and the fabric covering of the awning being shown in section; Fig. 2 is a plan view of the same; Fig. 3 is a side elevation similar to Fig. 1 and showing the awning fastener locked in 45 position on the attaching member, the building and the covering being shown in section; Fig. 4 is a front elevation of the awning fastener with the yoke in closed position; and Fig. 5 is a sectional side elevation of the same.

The covering A of the awning is made of the usual textile fabric and is provided at 50 its upper edge with a hem A' containing a filling A², such as rope and the like, to thicken the upper edge of the covering A. On this thickened edge of the covering A are slidably mounted awning fasteners B

each provided with a yoke C and each adapted to engage an attaching member D, such 55 as a screw eye, as shown in Figs. 1, 2 and 3, or a screw, nail or the like, as indicated in Fig. 5, the attaching members being permanently secured to the top of a window E or other structure on which the awning is used. 60 Each carrier B is provided at its lower portion with a keyhole slot B' to permit of engaging the carrier B endwise with the thickened end of the covering A and to allow of 65 sliding the carrier B along the said thickened edge to move the several fasteners in alinement with the corresponding attaching members D.

The ends of each carrier B are provided 70 with V-shaped bearings B² engaged by trunnions C' projecting inwardly toward each other from angular arms C² forming integral parts of the ends of the yoke C, which latter is preferably in the form of a bar extending lengthwise of the carrier B, as 75 plainly indicated in Figs. 2 and 4. By the arrangement described the yoke C can be shifted relative to the carrier B so as to move the yoke into an angular, open position relative to the carrier, as plainly indicated in Figs. 1 and 2, and the yoke can also 80 be shifted into an alined, closed position relative to the carrier, as shown in Figs. 3, 4 and 5. The free edge B³ of the carrier B is provided at or near its middle with a 85 notch B⁴, and the inner edge C³ of the yoke C is adapted to extend close to the edge B³ at the time the yoke C is in closed, alined position. The inner edge C³ of the yoke is 90 provided with a notch C⁴ adapted to register with the notch B⁴ of the carrier B to accommodate the shank of the attaching member D. When the yoke C is in angular, open 95 position, as shown in Figs. 1 and 2, then sufficient space is had for the passage of the head of the attaching member between the edge C³ of the yoke and the corresponding side of the carrier B to allow of passing the fastener inward on the attaching member D to the shank thereof, as will be readily understood by comparison of Figs. 1 and 2 with Fig. 3. When the yoke C reaches a 100 rearmost position on the attaching member D the carrier B is allowed to swing downward by the operator so that the covering A 105 now exerts a pull downwardly and out-

wardly on the carrier B to hold the latter and the yoke C in alined, closed position one relative to the other so that the head of the attaching member D is in front of the edges 5 B³ and C³ of the carrier B and the yoke C, and consequently the fastener cannot possibly slip off the attaching member D. By 10 making the bearings B² V-shaped the yoke C can be swung into angular, open position on either side of the carrier B according to the position of the attaching member D on the window or other structure. The outer wall of each bearing B² is provided at the apex with a recess B⁵ for engagement by the 15 corresponding trunnion C' at the time the yoke C is in alined, closed position relative to the carrier B so that the yoke C is not liable to swing into an open position in case gusts of wind or similar forces should move 20 the covering A upward while the awning is in the open position. The carrier B is provided with side openings B⁶ leaving a central portion B⁶ around which a wire may be 25 looped for supporting an awning pulley block, as indicated in dotted lines in Fig. 4.

The awning fastener shown and described is very simple and durable in construction and is composed of but few parts which can be readily placed in position on the thickened edge of the awning covering and moved 30 along the said thickened edge into register with the corresponding attaching member D so that the latter need not be disturbed at any time when placing the awning in position on the building or removing it therefrom. It will further be noticed that the 35 operator can conveniently engage the awning fasteners with the attaching members D, as it is only necessary to move the yoke C into an open, angular position relative to the carrier B and then slip the fastener onto the corresponding attaching member D, as 40 above described. When this has been done and the carrier is released, the pull exerted 45 by the covering A draws the carrier B and the yoke C into alined position in the rear of the head of the attaching member D.

It is understood that by the arrangement 50 described, rings, gromets, staples, hooks and similar devices are entirely dispensed with, as it is only necessary to slip the carrier endwise in position on the thickened edge of the awning and to attach the carrier on the attaching member D.

Having thus described my invention, I 55 claim as new and desire to secure by Letters Patent:

1. An awning fastener, comprising a fixed 60 attaching member having a head, and a carrier adapted to engage the edge of the awning covering and provided with a pivoted yoke, the latter when in angular position relative to the carrier being so positioned as

to allow engagement of the fastener with the attaching member, and the yoke when in 65 alinement with the supporting member and when in the rear of the said attaching member being so positioned as to hold the supporting member in locked position.

2. An awning fastener provided with a 70 carrier adapted to engage the edge of the awning covering and having its outer edge provided with a notch, and a yoke mounted to swing on the said carrier to assume an angular position or an alined position relative to the carrier, the yoke having an inner edge provided with a notch, the yoke when in alined position having its inner edge opposite the said notched edge and the notches 75 in register one with the other, and the yoke 80 when in angular position having its inner edge spaced from the corresponding side of the carrier for the passage of the head of a fixed attaching member on the window or other structure. 85

3. An awning fastener, comprising a carrier on the awning covering, and a yoke movable on the carrier and adapted to be moved into an open position for engagement 90 with a fixed attaching member on the window or other structure, and the yoke when in closed position locking the fastener in position on the attaching member and being held in locked position by the pull exerted by the awning covering. 95

4. An awning fastener, comprising a carrier having a keyhole slot slidingly engaging the thickened edge of an awning covering, the free edge of the said carrier being provided with a notch and the ends of the carrier being provided with bearings, and a yoke provided at its ends with trunnions engaging the said bearings to allow of swinging the yoke into an angular or into an alined position relative to the carrier, the yoke having a notch adapted to register with the said carrier notch. 105

5. An awning fastener, comprising a carrier having a keyhole slot slidingly engaging the thickened edge of an awning covering, the free edge of the said carrier being provided 110 with V-shaped bearings, and a yoke provided at its ends with trunnions engaging the said bearings to allow of swinging the yoke into an angular or into an alined position relative to the carrier, the yoke having a notch adapted to register with the said carrier notch. 115

6. An awning fastener, comprising a carrier having a keyhole slot slidingly engaging 120 the thickened edge of an awning covering, the free edge of the said carrier being provided with a notch and the ends of the carrier being provided with V-shaped bearings having notches in the outer walls at the 125 apexes of the said bearings, and a yoke pro-

vided at its ends with trunnions engaging the said bearings to allow of swinging the yoke into an angular or into an alined position relative to the carrier, the yoke having a notch adapted to register with the said carrier notch.

In testimony whereof I have signed my

name to this specification in the presence of two subscribing witnesses.

ANTHONY F. NUGENT.
